NIELS A. CHRISTENSEN, OF CLEVELAND, OHIO.

PISTON PACKING.

Application filed August 20, 1926. Serial No. 130,438.

The invention relates to piston packing. The object of the invention is to provide a piston packing of simple and efficient construction in which a thin metal packing disk is clamped at its central portion to the piston, and whose sealing flange engaging the bore is normally held against said bore by the inherent flexibility of a spring ring alone.

The invention further consists in the several features hereinafter set forth and more particularly defined by claims at the conclusion hereof.

In the drawings Fig. 1 is a vertical sectional view of a brake cylinder having its piston equipped with the packing construction embodying the invention;

Fig. 2 is a vertical sectional view through a compressor or motor piston equipped with the packing construction embodying the invention.

Referring to Fig. 1, the numeral 4 designates the main body of a brake cylinder having a bore 5 and closed at its ends by covers 6 detachably secured thereto by bolts 7.

As shown, a pair of pistons work in said bore 5 and move outwardly in opposite directions under the action of pressure fluid introduced into said cylinder between the pistons by way of a port 8 connected with a suitable source of supply.

Each piston includes a piston rod 9 slidably mounted in a guide bushing 10 in one of the covers 6 and having a reduced threaded end 11, a shoulder 12 and an exterior head 13. A piston head 14 in the form of a metal disk fits over the reduced end 11 and abuts against the shoulder 12.

The piston packing construction includes a thin metal cup 15 having an annular flange portion 16 engaging the bore 5 and a flat disk portion 17 abutting against the head 14 and fitting over the end 11 of the rod 9. The cup adjacent its central opening 18 is firmly clamped to the head by an annular plate 19 whose central opening has threaded engagement with the threaded end 11 of the rod 9. This plate 19 only engages the cup 15 at its central portion so that the greater part of its disk area is free but the cup being tightly clamped between the plate

19 and the head 14 serves as a gasket to prevent the escape of pressure fluid along the rod 11 past the head 14. The plate 19 in addition to acting as a clamp for the cup 15 also acts as a filler to reduce the clearance space in the pressure chamber so that the piston will respond quickly to differences in pressure existing in the pressure chamber, which in the form shown is between the pistons.

In order to normally hold the flange portion 16 of the cup in engagement with the bore 5 a spring ring 20, having the usual split joint, is adapted to fit within the sides or annular wall of the cup and by its inherent elasticity act against said flange portion. This ring, while generally similar to the usual piston rings, does not, as shown in the drawings, engage the flange 16 throughout its width but is preferably bevelled at its edges and relieved along an annular area at 22 so that it presses more particularly upon the outer edge portion of the sides of the cup or flange portion 16. The plate 19 has an annular projection 23 which extends over the front edge of the ring 20 but with a clearance space 24 therebetween to allow free action of the spring 20. A working clearance defined by the annular space 25 is provided between the plate 19 and the inner side of the ring.

When two pistons are used the followers or plates 19 abut each other when the pistons are in release position but owing to the fact that the annular portions 23 of these plates are spaced from the walls of the bore 5 and a groove or grooves 26 are provided in the faces of the plates 19, the air is free to enter or exhaust from the space between the plates.

With this construction, when the pressure fluid, such as compressed air, is introduced into the space between the piston it passes through the clearance spaces 24 and 25 and the clearance space 27, putting pressure upon the front face of the cup and expanding its sides against the bore 5, thereby providing a seal against the escape of air as the pistons are moved outwardly under this pressure. Upon the release of the pressure fluid

the sealing pressure of the cup against the cylinder is relieved except for the normal pressure of the spring ring 20. As the cup is only a few thousandths of an inch thick 5 it readily responds to the pressure within the chamber in which the piston works. By having the plate 19 only engage the central portion of the cup, the cup is, upon the release stroke of the piston, relieved to some 10 extent of the wall pressure.

In the construction shown in Fig. 2 the numeral 27 designates the main body of a compressor or motor piston which has a piston ring 28 adjacent the piston pin opening 15 29' for holding the piston pin, not shown, against longitudinal movement against the walls of the cylinder in which the piston works, should said pin become loose.

The body 27 of the piston has a threaded 20 projection 29 extending outwardly from its head 30. An annular follower piece or plate 31 fits over the projection 29 and a pair of oppositely disposed thin metal cups 32 and 33, together with a plate 34 interposed between the flat disk portions of the cups are 25 securely clamped together by a nut 35 engaging the threaded end of said projection 29 and seated in an annular recess 36 within the plate 31 and provided with spanner 30 wrench engaging openings 37. A spring ring 38, similar to the ring 20, fits within the cup 32 and exerts pressure against the sides thereof, and a similar spring ring 39 fits within the cup 33 and exerts pressure 35 against the sides thereof so that flanged portions of the cups, for a portion of their width, are held in engagement with the sides of the cylinder in which the piston works. The action of the cup 32 is similar to that 40 of the first described construction when pressure is built up in the cylinder above the top of the piston and where the same is used for a compressor the cup 33 acts during the suction stroke to prevent oil from passing by 45 the piston during said stroke, which might occur were the cup 32 used alone, owing to the tendency of the cup 32 to contract on account of the partial vacuum created during the intake stroke and thus oil pass by 50 the piston.

To keep the plate 31 out of contact with the bore of the cylinder and to act as a further seal, I provide a piston ring 40 seated in an annular groove 41 in said plate and in that event openings 42 are provided in said plate connecting a space 43, communicating with the pressure chamber, with the clearance spaces 44 and 45. Clearance spaces 46 and 47 are also provided adjacent the cup 33 60 and it is also to be noted that the plate 31 only engages the cup 32 at its central portion and the head of the piston only engages the cup 33 at its central portion, and that 65 these cups, clamped as they are between the

solid metal parts, act as gaskets to prevent gas leakage along the projection 29.

I desire it to be understood that this invention is not to be limited to any particular form or arrangement of parts except 70 as such limitations are specified in the claim.

What I claim as my invention is:

In a piston, the combination with the piston head and the cylinder in which the piston works, of a thin metal cup having its bottom abutting against the head, a member 75 securing the bottom portion of said cup in sealed contact with said head, and a split spring ring mounted within the sides of the cup and bevelled to normally act upon a limited area of the sides of the cup to press the cup against the bore of the cylinder solely by its inherent elasticity, said cup being expanded into sealing contact with the cylinder by pressure action upon the front of the 80 85 piston.

In testimony whereof I affix my signature.

NIELS A. CHRISTENSEN.
